LOCOMOTIVE CONSTRUCTION

Edwin W. Albers, Schenectady, N. Y.

Application May 19, 1933, Serial No. 671,812

20 Claims. (Cl. 105—172)

This invention relates to locomotives and particularly to locomotives wherein a plurality of driving trucks are employed and tractive and buffing forces are transmitted through the driving trucks and through a superstructure supporting frame. The invention is especially applicable to locomotives of the Garratt type which comprise two driving trucks pivotally articulated to a superstructure supporting frame.

10 An object of the present invention is to provide improved articulation means for driving trucks of the character aforesaid whereby tractive and buffing forces which have heretofore been transmitted through center plates and pins disposed between the driving trucks and locomotive superstructure supporting frames are transmitted separately and independently of center plates and pins, leaving the so-called center plates and pins to act as load-carrying and guiding elements (against lateral displacement) only.

15 A further object is to provide improved tractive and buffing force transmission means of the character aforesaid whereby such forces are transmitted more nearly in a straight line, i. e. one horizontal plane only, through the driving trucks and the superstructure supporting frame, than has been done in constructions of the prior art, thus minimizing undesirable twisting stresses caused by the transmission of such forces through several different horizontal planes as in prior practice.

20 A further object is to provide a locomotive embodying an improved arrangement of driving trucks, leading and trailing trucks and a superstructure supporting frame adapted to more efficiently effect load transmission and tractive and buffing force transmission through the trucks and supporting frame and to effect a saving in weight and a more economical, practical and serviceable construction than the constructions of the prior art.

25 Other and further objects of and advantages achieved by this invention will be apparent from the following detailed description and the appended claims.

30 An approved embodiment of this invention is illustrated in the accompanying drawings wherein Figure 1 is a side elevation of the forward portion of a locomotive embodying the present invention; Fig. 2 is a view similar to Fig. 1, of the rear portion of the locomotive; Fig. 3 is a vertical sectional view on an enlarged scale of one (the rear one) of the improved tractive and buffing force transmission means of the in-

vention, showing parts of the superstructure supporting frame and driving truck frame with which it is connected, the section being taken on the line III—III of Fig. 4; Fig. 4 is a plan view of parts of the structure shown in Fig. 3 with parts removed, a part being in horizontal section on the line IV—IV of Fig. 3 a part being broken away and certain parts above the section being indicated by dot and dash lines; Fig. 5 is a fragmentary side elevation on an enlarged scale of the connecting parts of a trailing truck frame and driving truck frame of the invention; and Figs. 6 to 10 are views of the superstructure supporting frame of the invention, Fig. 6 being a broken plan view, Fig. 7 a broken side view, Fig. 8 a front end view, Fig. 9 a section on the line IX—IX of Fig. 7, and Fig. 10 a rear end view.

35 Referring in detail to the drawings, the locomotive illustrated comprises two driving trucks 1 and 2 at the forward and rear ends of the locomotive respectively. Each of the trucks 1 and 2 embodies a frame 3 which includes side members having pedestal jaws and crosstie members, all of the usual construction. A superstructure 4, hereinafter more fully described is connected with the frames 3 and is supported in part by the driving trucks. A leading truck 5 and a trailing truck 6 are connected to each of the driving trucks at its outer and inner ends respectively, relative to the locomotive as a whole. In the drawings the locomotive is illustrated as facing toward the left and the trucks 5 have been termed leading trucks while the trucks 6 have been termed trailing trucks for the purpose of facility of expression, and will be so referred to hereinafter. It will however of course be understood that the locomotive is capable of running in a reverse direction as well as in a forward direction and it will therefore be apparent that the trucks 5 and 6 are respectively leading and trailing in fact only when the locomotive is running in a forward direction when considering the trucks at the forward end of the locomotive and only when the locomotive is running in a reverse direction when considering the trucks at the rear end of the locomotive.

40 A boiler 7 is carried by the frame 4 and suitably connected thereon by means of saddles 8 hereinafter more fully described and a cab 9 is supported at the rear of the boiler 7 upon the rear end of the frame 4. A water tank 10 is disposed forwardly of the boiler and is supported by the frame 3 of the driving truck 1, suitable supporting brackets 11 being disposed between

the tank and driving truck frame. The forward end of the tank 10 is supported on a cylinder saddle, which saddle together with power cylinders and valve chests is carried by the forward 5 end of the driving truck 1, which truck is in turn supported by the leading truck 5 at this end of the locomotive in the usual manner. The forward end of the driving truck 1 is connected to the leading truck 5 by a swiveling bolster connection of the usual construction.

10 A fuel container 12 is disposed rearwardly of the cab 9 and is supported by the frame 3 of the driving truck 2, suitable supporting brackets 13 being disposed between the frame 3 and the tank. The rear end of the tank 12 is supported on a cylinder saddle, which saddle together with power cylinders and valve chests is carried by the rear end of the driving truck 2, which truck in turn is supported by the leading truck 5 at this 15 end of the locomotive in the usual manner.

20 Each of the driving trucks 1 and 2 comprises four pairs of driving wheels 14, these driving wheels utilizing sufficient weight for proper tractive adhesion. The wheels 14 are connected with the driving trucks in the usual manner. Each of the leading trucks 5 is provided with four wheels 15. The trailing truck 6 connected to the driving truck 1 is provided with four wheels 16 and the trailing truck 6 connected with the driving truck 2 is provided with two wheels 17. The wheels of the leading and trailing trucks are connected to their respective truck frames in the usual manner and carry the remaining weight over and above that required for traction by the driving wheels of the driving trucks as hereininafter more fully described.

25 The superstructure supporting frame 4 is shown in detail in Figs. 6 to 10 inclusive and is formed as an integral casting comprising parallel, longitudinal, vertical side members 18 and parallel, vertical, transverse members 19 which extends between and connect the side members at spaced positions throughout their lengths. The longitudinal members 18 are depressed at their central portions 20, providing an open space or 30 pocket 21 into which the bottom portion of the fire box section 7a of the locomotive boiler 7 is disposed. The pocket 21 provides free access to the bottom portions of the sides of the fire box section 7a and to the stay bolts employed in the fire box section at these locations.

35 A pair of the transverse members 19 at each end of the pocket 21 is connected with a pair of the transverse members 19 at the adjacent end of the frame by a pair of longitudinal, vertical members 23, one member 23 being disposed on each side of the center line of the frame and spaced inwardly from its adjacent side member 18. Horizontal strengthening plates or webs 24 are provided at the upper and lower edges of the several longitudinal and transverse members, and the webs are cut away, providing a plurality of openings 25, as clearly shown in Fig. 6.

40 The saddles 8 hereinbefore referred to are integrally formed on the upper side of the frame 4 at the forward portion thereof, one being disposed at the forward end of the frame and the other being disposed adjacent the pocket 21. 45 Each of the saddles comprises a curved flange 26 and vertical strengthening members 22 which are continuations of adjacent transverse members 19 and longitudinal members 23 and connect the flange with the frame 4. The flange 26 of the front saddle is suitably secured by

5 bolts (not shown) to the smoke box section of the boiler 7 and the flange 26 of the rear saddle supportingly engages the barrel section of the boiler so as to permit relative longitudinal movement therebetween to compensate for expansion and contraction caused by varying temperatures.

5 A center plate 27 is integrally formed at each of the opposite extreme ends of the frame 4 at the under side thereof. A circular center pin 10 28 is suitably formed on each of the respective frames 3 of the driving trucks 1 and 2. The center plates 27 rest on the respective center pins 28, with a clearance between their adjacent vertical surfaces at their front and rear 15 portions, and a substantial part of the weight of the locomotive superstructure is transmitted from the supporting frame 4 through the center plates to the driving trucks.

20 It will be apparent that the weight carried by the driving trucks 1 and 2 includes weight of the superstructure carried by the frame 4 and the weight of the water tank and fuel container. The water tank and fuel container however rest directly upon the frames 3 of the trucks 1 and 2 respectively as hereinbefore described. The driving trucks are separated by a substantial space and each of the driving trucks is adapted to swivel about its center plate, moving relative to the superstructure supporting frame 4, 25 30 when the locomotive is passing through curved track.

25 As the center plates transmit load of both the superstructure and the frame 4, the driving trucks, in order to swivel, must always overcome the frictional resistance between the adjacent horizontal surfaces of the center plate and center pin imposed by this load. In designs of the prior art, wherein tractive and buffing forces are transmitted through the center 35 plates, the additional friction caused by these forces between the adjacent vertical surfaces of the center plate and center pin must also be overcome in order for the trucks to swivel. In the present invention however as the tractive and buffing forces are not transmitted through the center plates and center pins this additional cause of friction, between the adjacent vertical surfaces is not present and the amount of frictional resistance between the center plates and center pins when the trucks are swiveling is therefore materially less than in the designs of the prior art.

30 The tractive and buffing forces are transmitted through the driving truck and superstructure frames from one end of the locomotive to the other. Theoretically, these forces should be transmitted through a horizontal plane in the region of the driving wheel axles, the usual constructions being such as to cause these forces to be applied substantially in this plane. In 35 usual practice however these forces are transmitted from and to the superstructure frame through the center plate structure and thus the forces are transmitted through a broken path including vertical planes through the center pin structures, thereby producing objectionable twisting stresses in the frames. The present invention is directed to improving this condition by providing means for avoiding the necessity of transmitting these forces through the center plate structures and for transmitting these forces in a substantially straight horizontal path through the truck frames and the superstructure frame, thereby at least minimizing 40 45 50 55 60 65 70 75 80 85 90 95 100

said objectionable stresses. This is accomplished in the present instance by constructions comprising links and connecting pins, the pins being secured at both their ends to a frame, thereby presenting much stronger structures for the transmission of power than is possible with the usual center plate and center pin connections wherein each of these members is connected where anchored to its respective frame, at one end only, whereby twisting stresses are present when power is transmitted through such center plate and center pin connections from one frame to another.

The frame 4 is provided with a pair of spaced, longitudinal, vertical members 35 extending parallel to each other centrally of the frame. The members 35 are disposed between the members 23 at the end portions of the frame and at the central portion are depressed, correspondingly to the members 18. A pair of aligned annular bearing members 36 is provided near each of the opposite ends of the frame 4, spaced inwardly from the center plate at said end, one bearing member being formed in each of the respective longitudinal members 35. Beyond the bearing members the members 35 diverge outwardly and slant upwardly as indicated at 37. A bottom wall 38 extends from each of the center plates 27 inwardly or toward the middle of the frame 30 above the bearing members 36 and vertically downward at the inner sides of the bearing members, providing a pocket 48.

Each of the frames 3 of the driving trucks 1 and 2, at the location of its center pin 28, is constructed so as to provide a hollow structure including an upper horizontal wall 41, a lower horizontal wall 42 and a vertical wall 43 connecting the walls 41 and 42. The center pin 28 is formed integrally with the wall 41. Aligned openings 44 are formed in the center pin 28 and the wall 42, and annular flanges are provided around the openings 44 constituting bearings as hereinafter further described.

Ears 45 are provided one for connecting each end of the frame 4 with the respective driving truck frame 3 at said end. For the sake of brevity, only the bar at the rear end of the locomotive and its connecting structure will be described and it will be understood that the bar at the forward end of the locomotive and its connecting structure will be the same as the corresponding parts at the rear end except that the position of the bar is reversed end for end at the forward end of the locomotive. One end (forward in this particular instance) of the bar, see particularly Figs. 3 and 4, comprises a vertical, annular portion 46. Within the annular portion 46 an annular bushing 47 is mounted. The inner surface of the bushing 47 is concave and a substantially ball-shaped member 48 provided with a transverse opening 49 is disposed within the bushing 47. The bushing 47 is made in segments for the purpose of assembly. The transverse opening 49 is aligned with the openings of the annular bearing members 36 on the frame 4. Suitable bushings 50 are provided in the openings of the bearing members 36 and a pin 51 is passed through the bushings 50 and the transverse opening 49 of the ball shaped member 48, thus providing a universal connection. Lugs 52 are provided at one end of one of the bearing members 36 on opposite sides of its opening and the pin 51 is formed with a head 53 which rests against the outer face of said bearing member 36, limiting the extent to which

it may be inserted. A headed keeper pin 55 is passed through aligned openings 54 formed in the lugs and over the end of the head 53 for preventing accidental removal of the pin. The keeper pin 55 is held in place by a split key 55a.

The bar 45 converges vertically from front to rear and diverges horizontally in the same direction, presenting a structure of substantially the same cross-sectional area and strength throughout. The rear end of the bar is shaped to provide an annular portion 56 of substantially the same shape as the portion 46 excepting that the portion 56 is horizontally disposed as distinguished from the vertically disposed portion 46. Likewise, a pin 57 is provided at the rear end of the bar and is similar to the pin 51 excepting that it is vertically disposed instead of horizontally as the pin 51. Bushings and a ball shaped member are provided for the rear end of the bar, all of which parts are of the same construction and arrangement as the corresponding parts at the forward end of the bar excepting that at the rear end they are arranged to conform with the horizontal, annular portion 56 and vertical pin 57. The pin 57 is passed through the aligned openings 54 formed in the center pin 28 and the wall 42 hereinbefore described, suitable bushings 58 being provided around the pin in these openings. As aforesaid, the forward end of the frame 4 is connected to the frame 3 of the driving truck 1 by an identical bar structure and connecting parts as just previously described.

Referring now to the load transmission and the construction and connections between the leading and trailing trucks and the driving trucks and superstructure supporting frame, it will be understood that such transmission, construction and connections are substantially the same for each of the trucks 1 and 2 at the opposite ends of the frame 4 and the leading and trailing trucks adjacent thereto. For the purpose of brevity, only the trucks and connected parts at the rear end of the locomotive will be described.

The driving truck 2, as hereinbefore stated, is connected with its leading truck 5 in the usual manner, a suitable bolster (not shown) being provided for this purpose on the leading truck permitting swinging or relative lateral movement between the two connected trucks during operation as in usual practice.

The trailing truck 6 adjacent the rear driving truck 2, at its rear end supports the frame 3 of the truck 7 (see Fig. 5). This support is accomplished by means of a ball and socket connection indicated at 29. The connection 29 comprises a socket 30 carried on the upper surface of the adjacent end of the frame 31 of the trailing truck 6 and a ball member 32 carried on the under side of the frame 3 which ball member rests in the socket 30. A headed pin 33, provided with a split key, is passed through the ball member and socket preventing the connected parts from separating vertically. There is thus afforded a swivel bearing joint by the connection 29 and weight is transmitted to the trailing truck through this connection.

At the opposite end of this two-wheel trailing truck 6 supporting means for the superstructure supporting frame 4 are provided. These means comprise centering rockers 34 carried by the frame of the trailing truck, one on each of its opposite sides and disposed between the trailing truck frame and the superstructure support-

ing frame 4. Bearing seats 59, integrally formed on the opposite sides of the frame 4, are provided for the rockers 34, the rockers and their seats all being of usual well-known design and construction. In designs of the prior art the usual practice was to mount the axle of the wheels of the trailing truck in the frame of the driving truck, the driving truck frame being extended for this purpose and the support afforded by the trailing truck being supplied entirely to the frame of the driving truck. By the arrangement of the present invention the frame of the driving truck is terminated at the connection 29 and a substantial saving in weight of the driving truck thus effected and a more flexible wheel base thus provided.

Spring rigging and equalizers (not shown) are provided in the usual manner at opposite sides of the locomotive for each of the driving trucks. and their respective leading and trailing trucks.

The trailing truck 6 adjacent the forward driving truck 1 and its connecting structure with the superstructure supporting frame 4 and the frame of the driving truck 1 is as aforesaid the same as that just described with reference to the two-wheel truck 6 adjacent the rear driving truck 2 excepting that the trailing truck 6 adjacent the forward driving truck is a four-wheel truck.

In this type of locomotive heretofore a two-wheel trailing truck has been employed, articulated with a driving truck frame. In such constructions the frame of the driving truck has been extended over the trailing truck to the rear thereof and load-transmitting rockers have been interposed at the rear end, between the two truck frames. This presents a somewhat objectionable construction as when passing over curved track the driving truck frame extension swings laterally relative to the two-wheel truck and the consequent lateral projection of the extension must obviously be kept within the permissible bounds. In the present invention the driving truck frames as aforescribed are terminated adjacent the innermost pair of driving wheels thereby eliminating such extensions of their frames and the undesirable lateral projections thereof when the trucks are passing over curved tracks, and furthermore load-transmitting rockers are interposed directly between the superstructure supporting frame and the trailing truck frames.

While as stated it has been previously proposed to employ a driving truck frame with a rear extension connected with a two-wheel trailing truck, it is manifestly impracticable in such a construction to employ, instead of a two-wheel trailing truck, a four-wheel trailing truck. As is well known however a four-wheel truck is better adapted for supporting heavy loads than a two-wheel truck. Therefore the arrangement of the present invention employing a four-wheel trailing truck as described constitutes an additional advantage and an important feature of the invention.

While there has been hereinbefore described an approved embodiment of the present invention, it will be readily understood that many and various changes and modifications in the form, design, structure and arrangement of parts may be made without departing from the spirit of the invention and that all such changes and modifications are contemplated as a part of the present invention as defined in the appended claims.

The invention claimed and desired to be secured by Letters Patent is:

1. A locomotive comprising a superstructure having a supporting frame; a driving truck having a frame; a non-tractive-and-non-buffing-force-transmission connection permitting relative pivotal movement and preventing relative lateral movement, of said frames at said connection and serving to transmit load of said superstructure to said truck; and a rigid bar flexibly connected at its opposite ends with said supporting frame and said truck frame respectively, said bar serving as a tension member to transmit all tractive and buffering forces transmitted between said frames which are applied in one direction and as a compression member serving to transmit all tractive and buffering forces transmitted between said frames which are applied in the opposite direction.

2. A locomotive comprising a superstructure having a supporting frame; a driving truck having a frame; a connection permitting relative pivotal movement and preventing relative lateral movement, of said frames at said connection and serving to transmit load of said superstructure to said truck; and a rigid bar flexibly connected at its opposite ends substantially in the same plane with said supporting frame and said truck frame respectively for transmitting in said plane the entire tractive and buffering forces transmitted therebetween.

3. A locomotive comprising a superstructure having a supporting frame; a driving truck having a frame; a connection permitting relative pivotal movement and preventing relative lateral movement, of said frames at said connection and serving to transmit load of said superstructure to said truck; and a rigid bar independent of said connection flexibly connected at its opposite ends with said supporting frame and said truck frame respectively, said bar serving as a tension member to transmit all tractive and buffering forces transmitted between said frames which are applied in one direction and as a compression member serving to transmit all tractive and buffering forces transmitted between said frames which are applied in the opposite direction.

4. A locomotive comprising a superstructure having a supporting frame; a driving truck having a frame; a non-tractive-and-non-buffing-force-transmission connection permitting relative pivotal movement and preventing relative lateral movement, of said frames at said connection and serving to transmit load of said superstructure to said truck; and a rigid bar flexibly connected at its opposite ends with said supporting frame and said truck frame respectively, said bar serving as a tension member to transmit all tractive and buffering forces transmitted between said frames which are applied in one direction and as a compression member serving to transmit all tractive and buffering forces transmitted between said frames which are applied in the opposite direction, at least one of the bar connections being a universal connection.

5. A locomotive comprising a superstructure having a supporting frame; a driving truck having a frame; a non-tractive-and-non-buffing-force-transmission connection permitting relative pivotal movement and preventing relative lateral movement, of said frames at said connection and serving to transmit load of said superstructure to said truck; and rigid bar means serving as a tension member to transmit all tractive and buffering forces transmitted between said

frames which are applied in one direction and as a compression member serving to transmit all tractive and buffing forces transmitted between said frames which are applied in the opposite direction, said bar means having at one of its ends a pivotal connection with one of said frames, the axis of said pivotal connection being in alignment with the axis of said pivotal movement between said frames and having at the other of its ends a flexible connection with the other of said frames.

6. A locomotive comprising a superstructure having a supporting frame; a driving truck having a frame; a non-tractive-and-non-buffing-force-transmission connection permitting relative pivotal movement and preventing relative lateral movement, of said frames at said connection and serving to transmit load of said superstructure to said truck; a vertical pin carried by one of said frames; and a rigid bar serving as a tension member to transmit all tractive and buffing forces transmitted between said frames which are applied in one direction and as a compression member serving to transmit all tractive and buffing forces transmitted between said frames which are applied in the opposite direction, said bar being connected at one of its ends with said pin by a universal joint and flexibly connected at the other of its ends with the other of said frames.

7. A locomotive comprising a superstructure having a supporting frame; a driving truck having a frame; a connection permitting relative pivotal movement and preventing relative lateral movement, of said frames at said connection and serving to transmit load of said superstructure to said truck; a vertical pin mounted at its opposite ends in one of said frames; and a rigid bar connected at one of its ends with said pin by a universal joint disposed between said mounted ends and flexibly connected at the other of its ends with the other of said frames.

8. A locomotive comprising a superstructure having a supporting frame; a driving truck having a frame; a connection permitting relative pivotal movement and preventing relative lateral movement, of said frames at said connection and serving to transmit load of said superstructure to said truck; a vertical pin carried by one of said frames in alignment with the axis of said pivotal movement between said frames; a horizontal pin spaced from said first pin carried by the other of said frames; and a rigid bar connected at one of its ends by a universal joint with said vertical pin and pivotally connected at the other of its ends with said horizontal pin, said bar serving as a tension member to transmit all tractive and buffing forces transmitted between said frames which are applied in one direction and as a compression member serving to transmit all tractive and buffing forces transmitted between said frames which are applied in the opposite direction.

9. A locomotive comprising a superstructure having a supporting frame; a driving truck having a frame; a connection permitting relative pivotal movement and preventing relative lateral movement, of said frames at said connection and serving to transmit load of said superstructure to said truck; a vertical pin carried by one of said frames in alignment with the axis of said pivotal movement between said frames; a horizontal pin spaced from said first pin carried by the other of said frames; and a rigid bar of integral structure connected at one of its ends by a universal joint with said ver-

tical pin and pivotally connected at the other of its ends with said horizontal pin, said bar having oppositely disposed vertical faces converging from said universally connected end to its opposite end and oppositely disposed faces converging in an opposite direction to said vertical faces and connecting the opposite upper edges and the opposite lower edges respectively of said vertical faces.

10. A locomotive comprising a superstructure having a non-wheeled supporting girder-like frame; a superstructure load supporting truck pivoted to said frame at one end thereof; a driving truck having a frame disposed at the opposite end of said supporting frame; a non-tractive-and-non-buffing-force-transmission connection permitting relative pivotal movement and preventing relative lateral movement, of said frames at said connection and serving to transmit load of said superstructure to said truck; and rigid bar means serving as a tension member to transmit all tractive and buffing forces transmitted between said frames which are applied in one direction and as a compression member to transmit all tractive and buffing forces transmitted between said frames which are applied in the opposite direction, said bar means having a flexible connection at each of its opposite ends with each of said frames respectively.

11. A locomotive comprising a superstructure having a supporting frame; a driving truck having a frame; a connection permitting relative pivotal movement and preventing relative lateral movement, of said frames at said connection and serving to transmit load of said superstructure to said truck; and rigid bar means having at one of its ends a flexible connection with the truck frame below said load transmitting connection and at the other of its ends a flexible connection with said supporting frame, said flexible connections being substantially in the same plane.

12. A locomotive comprising a superstructure having a supporting frame; a driving truck having a frame flexibly connected with and supportingly engaging said supporting frame; and a truck at one end of said driving truck frame having a frame flexibly and supportingly engaging said supporting frame and flexibly and supportingly engaging said driving truck frame.

13. A locomotive comprising a superstructure having a supporting frame; a driving truck having a frame flexibly connected with and supportingly engaging an end of said supporting frame; and a trailing truck having a frame flexibly and supportingly engaging at its opposite ends said supporting frame and said driving truck frame respectively, one of said trailing truck engagements providing a pivotal connection between the two frames engaged thereby and the other of said trailing truck engagements permitting relative lateral movement between the two frames engaged thereby.

14. A locomotive comprising a superstructure having a supporting frame; a driving truck having a frame flexibly connected with and supportingly engaging an end of said supporting frame; and a four-wheeled trailing truck having a frame flexibly and supportingly engaging at its opposite ends said supporting frame and said driving truck frame respectively, one of said trailing truck engagements providing a pivotal connection between the two frames engaged thereby and the other of said trailing truck en-

- gagements permitting relative lateral movement between the two frames engaged thereby.
15. A locomotive comprising a superstructure having a supporting frame; a driving truck having a frame flexibly connected with and supportingly engaging an end of said supporting frame; and a four-wheeled trailing truck having a frame flexibly and supportingly engaging at its forward end the rear end of said driving truck frame and flexibly and supportingly engaging at its rear end said supporting frame, one of said trailing truck engagements providing a pivotal connection between the two frames engaged thereby and the other of said trailing truck engagements permitting relative lateral movement between the two frames engaged thereby.
16. A locomotive comprising a superstructure having a supporting frame; a driving truck having a frame flexibly connected with and supportingly engaging said supporting frame; and a second truck at one end of said driving truck frame having a frame flexibly and supportingly connected with said supporting frame and extending beneath and flexibly and supportingly engaging said driving truck frame, said second truck frame engagements being respectively disposed at opposite sides of an axle of said second truck.
17. A locomotive comprising a superstructure having a supporting frame; a driving truck having a frame flexibly connected with and supportingly engaging an end of said supporting frame; and a trailing truck having a frame flexibly and supportingly connected at one of its ends with said supporting frame and at the other of its ends extending beneath and flexibly and supportingly engaging said driving truck frame.
18. A locomotive comprising a boiler having a supporting frame; a driving truck having a frame; a container for fuel or water supported on said truck frame, said truck frame at one end extending beneath said supporting frame; a non-tractive-and-non-buffing-force-transmission connection permitting relative pivotal movement and preventing relative lateral movement, of said frames at said connection and serving to transmit load of said supporting frame to said truck frame; and rigid bar means having at one of its ends a flexible connection with one of said frames and having at the other of its ends a flexible connection with the other of said frames.
19. A structure for a locomotive comprising a longitudinal non-wheeled girder-like superstructure-supporting frame; means carried by and disposed at the bottom of said frame at one end thereof adapted to transmit superstructure load to a driving truck of said locomotive and for cooperation with means on said driving truck to permit relative pivotal movement and to prevent relative lateral movement, of said frame and truck at said connection; connecting means for a tractive-and-buffing-force-transmitting rigid bar of said locomotive, said connecting means being disposed in a vertical longitudinal plane passing centrally through said load transmitting means; and bearing means spaced from said load transmitting means, disposed at the bottom of said frame, adapted to transmit superstructure load to a trailing truck of said locomotive and adapted to cooperate with means on said trailing truck to permit relative horizontal angular movement between said frame and trailing truck.
20. A structure for a locomotive comprising a longitudinal non-wheeled girder-like superstructure-supporting frame; means carried by and disposed at the bottom of said frame at the opposite ends thereof adapted to transmit superstructure load to trucks of said locomotive; connecting means for tractive-and-buffing-force-transmitting rigid bars of said locomotive, one at each of the opposite end portions of said frame, the two said connecting means being disposed in a vertical longitudinal plane passing centrally through the two said load transmitting means; and a rigid longitudinal connection extending from one of said connecting means to the other in said vertical longitudinal plane and integral with said frame and the two said connecting means.
45. EDWIN W. ALBERS.
